Primary Examiner — Marissa J Cash*(74) Attorney, Agent, or Firm* — Flener IP & Business Law, LLC; Zareefa B. Flener**CLAIM**

The ornamental design for a vaporizer assembly, as shown and described.

DESCRIPTION

FIG. 1 is an exploded back perspective view of a vaporizer assembly showing a first embodiment of my new design; FIG. 2 is an exploded front and bottom perspective view of my new design illustrated in FIG. 1;

FIG. 3 is an exploded right elevational view thereof;

FIG. 4 is an exploded left elevational view thereof;

FIG. 5 is a back elevational view thereof;

FIG. 6 is a front elevational view thereof;

FIG. 7 is an exploded top plan view thereof;

FIG. 8 is an exploded bottom plan view thereof;

FIG. 9 is an exploded bottom and back perspective view thereof;

FIG. 10 is an exploded top and back perspective view of a second embodiment of my new design; and,

FIG. 11 is an exploded bottom and top perspective view thereof.
